COMBINED INITIAL AND PERCUSSION COMPOSITION

Wilhelm Eschbach and Heinrich Wippenhohn,
Troisdorf, Rhineland, GermanyApplication December 16, 1930, Serial No. 502,859
In Germany July 7, 1930

2 Claims. (Cl. 102—1)

This invention relates to a detonator having a combined percussion and priming charge.

In explosive bodies such as shells, torpedoes or the like which are detonated by the impact of a needle, first a percussion charge is ignited by the needle and then thereby the detonator charge. In many cases this manner of causing ignition is inexpedient chiefly because the percussion charge is separated from the detonator charge whereby a certain retardation is caused reckoned from the impact of the percussion needle until the detonation of the explosive charge, which in many cases is detrimental.

The present invention avoids this drawback by using a detonator which is so constructed that it makes the employment of a percussion cap or a special friction charge superfluous for igniting the priming charge of the detonator. At the same time it is possible by this means to construct detonators for projectiles, mines and the like in a much simpler and more effective manner than hitherto.

The object of this invention is to procure a combined priming and percussion charge by superimposing on the base or detonator charge, such as tetryl, a powerful explosive matter which can be depended upon to be ignited by the percussion needle and also to cause the detonation of the main or base detonator charge. The combined percussion and priming charge is covered by a prick foil and an inner cap and enclosed in a casing, the whole being fastened securely and shock-proof in a cartridge case.

Suitable compositions for the combined percussion charges for this purpose are the ordinary detonator compositions as for instance azides of heavy metals, fulminate of mercury or the like, the sensitiveness against blows and friction being raised to the desired degree by suitable admixtures of gritty matter, such as powdered glass or quartz, as well as other matter such as "tetracene" and silicide. The scientific term for "tetracene" is guanylitosaminoguanyl tetracene, which has the following formula:

Compositions for this combined percussion and priming charge suitable for this purpose may also be obtained by substituting the inflammable components in the usual friction charge, such as chlorate of potassium and sulphide of antimonium, by blasting explosives as for instance pentaerythritetetrinitrate.

In the accompanying drawing, Figure 1 is an axial section of an old type detonator; Figure 2 is

a similar view of a detonator in accordance with the present invention, and Figure 3 a similar view of such a detonator assembled in a shell.

The accompanying drawing shows in section a detonator *k* which has been filled by the method 60 previously usual, see Figure 1, and a similar detonator *l* filled in accordance with this invention, Figure 2. In Figure 1, *a* is the friction charge, *b* is the priming charge and *c* is the base or detonator charge. It is seen, therefore, that the detonator is divided into three parts *a*, *b*, *c* in the old kind of detonator. In Figure 2 the detonator *l* contains only two explosive charges, viz. the combined priming and percussion charge *d* superimposed on the base charge *c* as provided by the 70 present invention. The combined percussion and priming charge *d* is placed on top of the base charge *c* in a casing *n* which is closed at the top by the prick foil *o* and perforated inner cap *m*.

The arrangement of the new detonator in a 75 shell is shown in Figure 3. In this figure, *e* is the needle, *f* the ignition head, *d* the combined priming and percussion of the detonator *l*, *g* the shell body and *h* the bursting or explosion charge.

80
We claim:

1. A detonator comprising a base charge and a combined priming and percussion charge, containing substances capable of increasing sensitiveness towards impact and friction, so that the said combined charge may be fired by the impact 85 of the needle to cause detonation of said base charge.

2. A detonator according to claim 1 in which said substances are selected from a group consisting of guanylitosaminoguanyl tetracene, and 90 silicide.

WILHELM ESCHBACH.
HEINRICH WIPPENHOHN.
